UNITED STATES PATENT OFFICE.

LOUIS J. VAN GUELLEN AND WILLIAM STUEBING, JR., OF CINCINNATI, OHIO.

BURNISHING-MACHINE.

1,227,221.

Specification of Letters Patent. Patented May 22, 1917.

Application filed January 10, 1916. Serial No. 71,262.

To all whom it may concern:

Be it known that we, LOUIS J. VAN GUELLEN and WILLIAM STUEBING, Jr., both citizens of the United States, and both residents of the city of Cincinnati, in the county of Hamilton and State of Ohio, have invented certain new and useful Improvements in Burnishing-Machines, of which the following is a specification.

10 The object of our invention is to produce a machine for burnishing any kind of a material of varying shape, size and contour, such for example as vamps for shoes.

15 Its salient feature consists in providing a revolving burnishing tool or spindle operating in connection with feeding mechanism.

20 Another feature consists in providing a peripheral slot or groove in said tool into which the material to be burnished extends while said tool is revolving.

Another feature consists in unique means for heating the burnishing tool.

25 Its other features and advantages will readily become apparent from the following specification.

In the accompanying drawings forming part of this specification:

Figure 1, is a sectional view on line 1—1
30 of Fig. 3,

Fig. 2, is a side elevation of the machine,
Fig. 3, is a plan view of the same,

Fig. 4, is a section on line 4—4 of Fig. 1,
Fig. 5, is a front view of Fig. 2 showing

35 lower part of machine with the oil box
broken away to illustrate construction,

Fig. 6, is a plan view of part of the feeding mechanism, parts being broken away to show the same,

40 Fig. 7, is a plan view of the machine
broken away to show driving mechanism
and connections,

Fig. 8, is an enlarged detail view of the
45 upper part of the parts shown in Fig. 4
referring particularly to the electrical
connections of the heating unit, and

Fig. 9, is a plan view of Fig. 8, partly
broken away to show brush connections.

50 The base of the machine, in the present
instance, consists of an oil box or pan 1,
on which is mounted at the top the upper
plate 2 by means of screws 3 and 4, which
plate has depending arms 5 and 6, fastened
at their extremity to a lower plate 7 by
55 means of screws 9.

Upon the upper surface of plate 2 at its

rear, we connect the upward and forward
extending arm 10, by means of screws 12
and 13. In the forward end of said arm
10 we provide a screw threaded bearing 14,
60 to admit the upper center screw 15. On
this screw 15, we place the nut 16 which
allows said screw to be locked into place.

In the lower plate 7 and in perpendicular
alinement with the upper center screw 15,
65 we provide the lower center screw 17 which
may be locked if desired, same as the upper
center screw.

Between these two center screws 15 and
17, we provide and place the vertical revolv-
70 ing spindle 18 made up of parts which we
will now describe. The upper portion of
spindle 18 consists of a cylinder 19 cored
out in its center to admit the heating unit
20; fastened to the upper face of said cyl-
inder 19, we provide the housing 21, se-
cured in place by the screws 22 and 23;
between the housing 21 and cylinder 19, we
place a non-conductor, in the present in-
stance being mica pads 24; the housing 21
80 in its upper position has a center bearing
25, which revolves around the center screw
15; the housing also carries a cup 26 for
carrying oil to lubricate the screw and bear-
ing, having a cap 27; the housing 21 has
85 two outwardly extending arms 28 and 29,
upon which we fasten the mica pads 30
and 31, for insulation purposes, these pads
being held in position by screws 32; on top
of the mica pads 30 and 31, we secure the
90 two rings 34 and 35 by means of screws 36
and 37, thus insulating the rings 34 and
35 from the housing 21. Connected to the
ring 34 is an electric wire 38 and connected
95 to the ring 35 is a wire 39, thus forming
a positive and negative connection to the
electric unit, see Fig. 8 particularly. Fas-
tened to the arm 10, at point 40, we provide
the bar 41 to be made of suitable insulating
material, and also connect to bar 41, the
100 positive brush 42 and the negative brush
43. To the brush 42, we provide a screw
44 and to brush 43, we provide screw 45,
which screws hold the electrical feed wires,
not shown.

At the middle of the spindle 18, we place
the stud end 46 of the lower cylinder 47, up
into the space 48 of which cylinder, we ex-
tend the stud end 49 of the driving gear 50.
In the lower part of gear 50, we provide the
110 center bearing 51, which revolves around the
center screw 17.

Through the following means we revolve the spindle 18, to wit: In lower plate 7, we provide a bearing 52 and at the point 53, we fasten the upward and forward extending 5 arm 54, by means of screw 55. In the forward end of arm 54 is a bearing 56 in perpendicular alinement with the bearing 52. We provide a perpendicular shaft 57 revolving in the bearings 56 and 52, and on shaft 57 we fasten the gear wheel 58 which meshes with the gear wheel 50 on spindle 18, thus revolving said spindle. On the upper end of shaft 57, we place the miter gear 59. On a horizontal shaft 60 in bearing 61 on 15 plate 2 and bearing 62 on the depending arm 5 and bearing 63 on depending arm 6, we place the miter gear 64 which meshes with miter gear 59 on shaft 57, thus imparting motion to said shaft 57. On the shaft 60 we 20 place a pulley 65. On this same shaft 60, at its forward end, we place a gear wheel 66. In the depending arm 5, we place a stud 67 which is locked into position by nut 68. The lower feed roller 69 revolves on the forward 25 end of the stud 68, and fastened on the hub end of said feed roller 69, we place the gear wheel 70 which meshes with gear wheel 66 on shaft 60, see particularly Fig. 7, and thus driving the lower feed roller.

30 To arm 10 we connect the forwardly and downwardly extending arm 71, by means of screws 72 and 73. Said arm 71 also extends around the spindle 18 as shown in Fig. 6.

In the forward end of arm 71, we place a 35 sliding bearing 74 so that the upper feed roller 75 can move up and down. In the sliding bearing 74, we provide the bar 76 which, at its lower end, extends forward and thus supports and holds the stud 77 on 40 which the upper feed roller 75 revolves.

The bar 76 is held in position by means of the straps 78 and 79. A downward pressure is exerted upon the roller 75 through means of spring 80, which is connected at its lower 45 end at point 81 on strap 79 and at its upper end is connected at point 82 to bar 76.

In the spindle 18, we place a peripheral slot 83 of any desired size and contour. It will be noted that the spindle or burnishing 50 tool 18 extends through plate 2 as does also the lower feed roller 69. The feed rollers 75 and 69 feed the material and hold it in place in the slot 83 in the revolving spindle 18, said feed rollers being so placed that the material to be burnished can readily be fed into the slot 83.

Through the mechanism described the 55 burnishing tool, which is the spindle 18, revolves in the same direction as the feed of the material, the best results are obtained however by driving the spindle or burnishing tool considerably faster than the feed of the material.

It will readily become apparent that this 60 machine can be operated very rapidly and

continuously and the burnishing can be done uniformly and evenly.

From the above description it will be seen that the improved burnishing machine, constructed according to our invention, is of an extremely simple and inexpensive nature, and is especially well adapted for the purposes for which it is designed, and it will also be obvious from the above description that the burnishing machine is capable of considerable modification, without material departure from the principle and spirit of the invention, and for this reason we do not wish to be understood as limiting ourselves to the precise form and arrangement of the several parts of the device as herein set forth in carrying out our invention in practice.

What we claim as new and our invention and desire to secure by Letters Patent is:

1. In a burnishing machine, a revolving 85 burnishing tool, combined with heating means, said heating means revolving with said tool, said burnishing tool having a peripheral groove constructed and arranged to receive the edge of the material to be burnished, and means for feeding the material through said groove.

2. In a burnishing machine, a revolving 90 burnishing tool, a hollow portion in said burnishing tool, a heating device fitting in said hollow portion and revolving with said burnishing tool, said burnishing tool having a peripheral groove constructed and arranged to receive the edge of the material to be burnished, and means for feeding the material to and through said groove.

3. In a burnishing machine, a spindle carrying within it means for heating the same and revolving with said means, said spindle having a peripheral groove constructed and arranged to receive the edge of the material to be burnished, and means for feeding the material through said groove while the spindle is revolving.

4. In a burnishing machine, a revolving 105 spindle carrying heating means within it and provided with a peripheral groove constructed and arranged to receive the edge of the material to be burnished, and feeding means for moving the material through said groove in the same direction as the surface of the spindle at the point of contact with the material.

5. In a burnishing machine, a revolving 110 spindle carrying heating means within it and provided with a peripheral groove constructed and arranged to receive the edge of the material to be burnished, and means for feeding the material through said groove in the same direction as the surface of the 115 spindle at the point of contact with the material, the revolving spindle having a surface speed faster than that of the feeding mechanism.

6. In a burnishing machine, a hollow re- 120

- volving burnishing tool carrying an electric heating unit within it, and means for transmitting the current to the said heating unit as the burnishing tool is revolving, said tool 5 provided with a peripheral groove constructed and arranged to receive the edge of the material to be burnished, and means for feeding the material into and through said groove.
7. In a burnishing machine, a revolving spindle formed of an upper and a lower part suitably joined together and supported between upper and lower center bearings, said spindle carrying heating means within it 15 and provided with a peripheral groove constructed and arranged to receive the edge of the material to be burnished, and means for feeding the material into and through said groove.
8. In a burnishing machine, a revolving burnishing tool provided with a peripheral groove constructed and arranged to receive the edge of the material to be burnished, said tool carrying an electric heating unit, 20 and means for feeding the material to and through said groove.
9. In a burnishing machine, a vertically disposed and suitably supported revolving spindle, a heating unit within said spindle 25 for transmitting heat thereto while the same is revolving, said spindle provided with a peripheral groove constructed and arranged
- to receive the edge of the material to be burnished, and means for feeding the material to be burnished into and through said 35 groove.
10. In a burnishing tool, a burnishing element and a heating element combined together to form a single revolving tool, said tool having a peripheral groove constructed 40 and arranged to receive the edge of the material to be burnished.
11. In a burnishing tool, a burnishing element and a heating element combined together to form a single revolving tool, said 45 tool having a peripheral groove constructed and arranged to receive the edge of the material to be burnished, and means for feeding the material to be burnished to and through said groove.
12. In a burnishing machine, a revolving spindle carrying heating means, and provided with a peripheral groove constructed and arranged to receive the edge of the material to be burnished, and means for feeding the material through said groove, the 50 revolving spindle having a surface speed faster than that of the feeding mechanism.
